MINING APPARATUS

Morris P. Holmes, Claremont, N. H., assignor to
 Sullivan Machinery Company, a corporation of
 Massachusetts

Application July 10, 1931. Serial No. 549,952

18 Claims. (Cl. 262—28)

This invention relates to mining apparatus, and more particularly, but not exclusively, to improvements in coal mining apparatus of the track supported and guided type adapted to operate 5 from the mine trackway.

An object of this invention is to provide an improved coal mining apparatus. Another object is to provide an improved coal mining apparatus of the track supported and guided type adapted to 10 operate from the mine trackway. A further object is to provide an improved propelling mechanism for such an apparatus. Still another object is to provide an improved propelling mechanism for a mining apparatus of the aforesaid character, 15 which is supplemental to the usual truck wheel driving mechanism. Yet another object is to provide in such a mining apparatus an improved haulage means supplemental to the truck wheel driving mechanism for propelling the apparatus 20 along the mine trackway, said supplemental haulage means under certain conditions complementing the truck wheel driving mechanism in the propulsion of the machine along the mine trackway. A further object is to provide an improved haulage 25 means for a mining apparatus of the track supported and guided type including a power winding device and a cooperating draft element. A still further object is to provide an improved supplemental propelling means for a mining apparatus of the track supported and guided type 30 including a haulage means and a cooperating draft element, the latter connectible to an extraneous abutment whereby, in case the tractive effort of the truck wheel drive is insufficient to 35 propel the apparatus with the necessary power, the same may be augmented or at times supplanted by the improved supplemental haulage means. These and other objects and advantages of the invention will, however, subsequently more fully 40 appear.

In the accompanying drawings there is shown, for purposes of illustration, one form which the invention may assume in practice.

In these drawings,—

Fig. 1 is a plan view of a coal mining apparatus having embodied therein the illustrative embodiment of the improved supplemental haulage means.

Fig. 2 is a side elevational view of the apparatus shown in Fig. 1.

Fig. 3 is a horizontal sectional view taken substantially on line 3—3 of Fig. 2, parts being shown in plan to facilitate illustration.

Fig. 4 is a transverse vertical sectional view 55 taken substantially on line 4—4 of Fig. 3.

Fig. 5 is a perspective view illustrating the improved supplemental haulage means.

In this illustrative embodiment of the invention, the improved supplemental haulage means, generally designated 1, is, for illustrative purposes, shown embodied in a coal mining apparatus of the same general character as that disclosed in the patent to Morris P. Holmes, No. 1,785,961, patented Dec. 23, 1930; although it is evident that the improved supplemental propelling means may be utilized in an equally effective manner with mining apparatus of various other types. This mining apparatus is of the combined horizontal and shear cutter type and generally comprises a main frame 2 mounted on adjustable front and rear supports 3 and 4, respectively, herein comprising swingable arms supported on truck wheels 5 adapted to run along a usual mine trackway 6. Supported on the main frame 2 for rotation about a longitudinal axis within spaced bearing means 7 and 8, is a rotatable support 9 having attached thereto at its forward end a cutter head 10. Pivotal mounted on the cutter head for swinging movement relative thereto is a cutter bar 11 which carries on its margin a usual cutter chain 12. The support 9 houses a motor 13 which drives the mechanisms for rotating the support 9, swinging the cutter bar 11, actuating the cutter chain 12, as hereinafter described, the mechanism for driving the truck wheels and the improved supplemental haulage means 1. As described in the above mentioned patent, the supports 3 and 4 may be adjusted either simultaneously or one independently of the other to effect adjustment 90 of the main frame 1 together with the cutting mechanism carried thereby into different elevated positions relative to the trackway and into tilted positions about a transverse axis to change the angle in altitude of the cutting mechanism, as conditions may require. As the specific construction of the mechanisms for rotating the support, for swinging the cutter bar, and for actuating the cutter chain does not enter into this invention, further description of the same is 95 thought unnecessary.

Now referring to the truck wheel driving mechanism, it will be noted that the power shaft 14 of the motor 13 has keyed thereto a spur pinion 15 meshing with a spur gear 16 suitably secured to a longitudinally extending shaft 17. Also secured to this shaft and driven thereby is a spur gear 18 meshing with a spur gear 19 secured to a shaft 20, herein arranged parallel with the shaft 17, as shown in Fig. 4. Keyed to the shafts 110

17 and 20, respectively, are worms 21 and 22, meshing, respectively, with fast and slow speed worm wheels 23 and 24. These worm wheels are herein coaxially arranged and are suitably journaled on a horizontal shaft 25, herein arranged transversely of and suitably journaled within the main frame 2. These worm wheels are selectively connectible to the shaft 25 by multiple disc clutches 26 and 27, respectively; and these 10 clutches have suitable operating means so that when one clutch is applied the other is released. It is therefore evident that the shaft 25 may be driven at either a high or a low speed, depending upon which one of the clutches 26 and 27 is applied. Keyed to one end of the shaft 25 is a bevel gear 28 meshing with reverse bevels 29 and 30 suitably rotatably supported by a longitudinally extending shaft 31, the latter in turn being suitably journaled on the side of the main 20 frame 2. These reverse bevels are selectively connectible to the shaft 31 by multiple disc clutches 32 and 33, respectively, having any suitable form of operating means so that when one or the other of these clutches is applied, the shaft 31 may be driven in one direction or the other. As shown in Fig. 3, connected by a coupling 34 to the shaft 31 is an alined shaft 35, suitably journaled on the machine frame and having keyed thereto at its forward end a bevel gear 36 meshing with a bevel gear 37 suitably rotatably supported on a horizontal transversely extending shaft 38. The bevel gear 37 is connectible to the shaft 38 by a sliding clutch 39, and keyed to the outer end of this shaft is a chain sprocket 40. This chain sprocket is connected by an endless chain connection 41 to a sprocket 42 arranged with its axis coincident with the pivotal axis of the rear support 4. The sprocket 42 is connected in driving relation with the rear support wheel through a chain and sprocket connection 43, and to the front support wheels through chain and sprocket connections 44 and 45, in the manner clearly described in the above mentioned patent. It will thus be seen that the 45 truck wheels may be driven to propel the apparatus along the mine trackway at either a relatively high or a relatively low speed under the control of the speed controlling clutches 26 and 27, and that the truck wheels may be driven in either of opposite directions under the control of the reverse frictions 32 and 33. The truck wheel driving mechanism described above is clearly disclosed in the above mentioned Holmes patent.

50 55 The improved supplemental propelling mechanism 1 for propelling the apparatus along the mine trackway is driven through the fast and slow speed gearings 21, 23 and 22, 24 under the control of the disc clutches 26 and 27 and the reverse frictions 32 and 33, and herein includes a shaft 46 which is herein an extension of the shaft 38, and journaled on this shaft is a haulage drum 48. This haulage drum is connectible to the shaft 46 by a multiple disc clutch 49. The haulage drum is provided with rope winding surfaces 50 and 51 separated by a radial flange 52, herein disposed intermediate the inner and outer drum flanges 53 and 54. The shaft extension 46 is journaled in a ball bearing 55 supported by a bracket 56 suitably attached to the machine frame, and mounted on this shaft extension are bearing sleeves 57, 57 on which the drum hubs are rotatably mounted. The outer hub 58 of the drum is externally threaded at 59 65 and has threadedly connected thereto a clutch

applying member 60 engageable with a pressure plate 61 for pressing the clutch discs of the friction clutch 49 together to apply the clutch 49, and the drum is retained on the shaft extension by a retaining washer 62 held in position by a holding nut 63 threadedly connected to the reduced outer end 64 of the shaft 46. Wound upon the haulage drum is a draft cable 65, so that when the drum when viewed as shown in Fig. 2, rotates in a counter-clockwise direction, the draft cable is wound upon the winding surface 50 of the drum. To enable winding in of the draft cable 65 during rotation of the drum in a clockwise direction without rewinding the cable on the drum surface 50, the intermediate drum flange 52 is slotted at 66 and the slotted ends of this flange are rounded at 67 to form abutments, so that the cable 65 may be passed from the winding surface 50 through the slot 66 and wound upon the winding surface 51 in an opposite direction so that as the drum is rotated in a clockwise direction the cable is wound in on the winding surface 51 of the drum. The draft cable 65 is adapted to be extended rearwardly from the drum around a guide sheave 68 rotatably supported by a bracket 69 attached to one side of the machine frame adjacent the rear end thereof, as shown in Figs. 1 and 2. 80 85 90 95 100 105 110 115 120 125 130 135 140 145 150

The operation of the improved mining apparatus will now be described. The apparatus may be propelled along the mine trackway at a relatively high transport speed under the control of the fast speed control clutch 26 and the friction clutch 33. The truck wheels are driven from the motor 13 at a high transport speed through the spur gearing 15, 16, worm gearing 21, 23, bevel gearing 28, 30, shafts 31, 35, bevel gearing 36, 37, and the chain and sprocket connections 41, 43, 44 and 45. If it is desired to propel the apparatus along the mine trackway in the reverse direction at a relatively high speed, the friction clutch 33 is released and the reverse friction 32 applied, and as a result the truck wheels are driven at a high speed in a reverse direction. During the cutting operation, the cutting mechanism is operated to cut a kerf in the coal face, and the sumping and withdrawal cuts are effected by propelling the apparatus bodily along the mine trackway at a relatively low cutting speed. The relatively low speed drive of the truck wheels for propelling the apparatus forwardly along the mine trackway is effected by the motor 13 through transmission gears 15, 16, 18, 19, worm gearing 22, 24, bevel gearing 28, 30, shafts 31, 35, bevel gearing 36, 37, and the chain and sprocket connections 41, 43, 44 and 45. The apparatus may be propelled rearwardly along the trackway at a low cutting speed simply by releasing the friction clutch 33 and applying the reverse friction 32, thereby effecting reversal of the truck wheel drive. If for any reason the truck wheels slip relative to the track rails during the cutting operation and their tractive effort is insufficient for propelling the machine along the mine trackway to effect sumping and withdrawal movements of the cutter bar, the truck wheel driving mechanism may be supplemented and at times supplanted by the improved supplemental haulage means 1. When it is desired to propel the apparatus by means of the haulage drum 48, the draft cable 65 is unwound from the drum and extended to a point in advance of the apparatus and anchored at its free end. If it is desired to wind in the draft cable at a speed appropriate to effect propulsion 170

- of the apparatus at a cutting speed, the friction clutches 27 and 33 are applied, thereby effecting rotation of the drum 48 in winding direction at a relatively low speed. Upon reversal of the 5 truck wheel drive, the drum 48 is simultaneously reversed, and to enable the drum to wind in the cable to effect propulsion of the apparatus along the mine trackway in the reverse direction during reverse truck wheel drive, the free end of 10 the cable may be passed through the slot 66 in the drum flange 52 and wound in a reverse direction around the winding surface 51 of the drum so that when the direction of truck wheel drive is reversed by applying the reverse friction 32, 15 the drum 48 will still wind in the cable without rewinding of the cable on the drum surface 51. It will also be evident that the cable 65 may be extended in a forward or rearward direction from the drum so that while the drum rotates 20 in a single direction the draft cable may be wound in to propel the apparatus either forwardly or rearwardly. The drum 48 may be entirely disconnected from its drive at will simply by threading the member 60 outwardly along the 25 drum hub to release the disc clutch 49.

As a result of this invention, it will be noted that an improved mining apparatus of the track supported and guided type is provided, having improved propelling means whereby it is possible 30 to supplement the truck wheel drive in case the truck wheels slip relative to the track rails, for instance when the machine is effecting its summing and withdrawal cuts or moving along a steeply inclined trackway. It will further be noted that 35 an improved supplemental haulage means is provided whereby when the haulage drum is rotated in either of opposite directions, the draft cable may be still wound in without rewinding thereof on the drum, simply by passing the free end of 40 the cable through the slot in the intermediate drum flange and winding the cable in the reverse direction on the winding surface 51 of the drum. It will also be noted that the improved supplemental haulage mechanism may be embodied in a 45 mining apparatus of a standard design with a minimum of change and expense the haulage means being driven through the truck wheel driving mechanism under the control of the speed control clutches and the reverse frictions which 50 also control the truck wheel drive. These and other uses and advantages of the improved mining apparatus will be clearly apparent to those skilled in the art.

While I have in this application specifically described one embodiment which my invention may assume in practice, it will be understood that this form is shown for purposes of illustration only, and that the invention may be modified and embodied in various other forms without departing from its spirit or the scope of the appended claims.

What I claim as new and desire to secure by Letters Pa'ent is:—

1. In a mining apparatus, feeding mechanism 65 comprising a haulage drum, a draft cable thereon, and having a single free end connectible to an extraneous abutment and means for rotating said drum in either of opposite directions, said drum having means whereby when said cable is partially wound on said drum, said cable may be further wound in by said drum to effect feed of the apparatus in either of opposite directions irrespective of the direction of rotation of said drum and without rewinding of the cable on said 70 drum.
2. In a mining apparatus, feeding mechanism comprising a haulage drum having a plurality of cable winding surfaces, and a draft cable wound on said drum in opposite directions about said surfaces and having a single free end, mechanism for rotating said drum in winding direction at either a high or a low speed, and mechanism for reversing the direction of drum rotation at will, the cable being so arranged on said drum that irrespective of the direction of drum rotation and 75 without completely rewinding the cable on the drum the cable may be wound in to effect feed of the apparatus in either direction. 80
3. In a mining apparatus, feeding mechanism comprising a haulage drum having a plurality of cable winding surfaces and a draft cable wound on said drum in opposite directions about said surfaces and having a single free end, a drive shaft on which said drum is rotatably supported, and clutch means for connecting said drum directly to said shaft, the cable being so arranged on said drum that irrespective of the direction of drum rotation and without completely rewinding the cable on the drum the cable may be wound in to effect feed of the apparatus in either direction. 85
4. In a mining apparatus, feeding mechanism comprising a haulage drum having a plurality of cable winding surfaces and a hub, a draft cable wound on said drum in opposite directions about 90 said surfaces and having a single free end, a drive shaft on which said drum is rotatably supported and clutch means for connecting said drum directly to said shaft, and operating means for said clutch means including an operating member threadedly connected to the drum hub, the cable being so arranged on said drum that irrespective of the direction of drum rotation and without completely rewinding the cable on the drum the cable may be wound in to effect feed 95 of the apparatus in either direction. 100
5. In a mining apparatus, the combination with cutting mechanism and propelling means for said cutting mechanism, of supplemental propelling means for the cutting mechanism 105 including a haulage drum having a plurality of cable winding surfaces, and a draft cable having a single free end and wound in opposite directions about said surfaces on said drum, said cable being so arranged on the drum that one portion 110 thereof when wound on one of said surfaces effects feed of the apparatus in one direction and another portion thereof wound on the other drum surface effects feed of the apparatus in the opposite direction. 115
6. In a mining apparatus, the combination with cutting mechanism and propelling means for said cutting mechanism, of supplemental propelling means for the cutting mechanism including a haulage drum having a plurality of cable 120 winding surfaces, and a draft cable wound in opposite directions about said surfaces on said drum, and having a single free end, the cable being wound on one winding surface in one direction and having its free end wound on the other surface in the reverse direction, the portion 125 of said cable wound on one surface effecting feeding of the apparatus in one direction and the other portion wound on the other surface effecting feed of the apparatus in the opposite direction. 130
7. The combination with a mining apparatus of the wheel mounted type adapted to run along the mine trackway and having kerf cutting mechanism adapted to operate while the ap- 135

- paratus is supported and guided by the mine trackway, of propelling means for the apparatus comprising a haulage drum, a draft cable thereon and having a single free end connectible 5 to an extraneous abutment, and means for rotating said drum in either of opposite directions, said drum having means whereby when the cable is partially wound on said drum, said cable may be further wound in by said drum to effect 10 propulsion of the apparatus along the trackway in either direction irrespective of the direction of rotation of the drum and without rewinding of the cable on the drum.

8. The combination with a mining apparatus 15 of the wheel mounted type adapted to run along the mine trackway and having kerf cutting mechanism adapted to operate while the apparatus is supported and guided by the mine trackway and means for propelling the apparatus by the drive 20 of the supporting wheels thereof, of supplemental propelling means for the apparatus operable simultaneously with the support wheel driving means comprising a haulage drum, a draft cable thereon and having a single, free end connectible 25 to an extraneous abutment, and means for rotating said drum in either of opposite directions, said drum having means whereby when the cable is partially wound on said drum, said cable may be further wound in by said drum to effect 30 propulsion of the apparatus along the trackway in either direction irrespective of the direction of rotation of the drum and without rewinding of the cable on the drum.

9. The combination with a mining apparatus 35 of the wheel mounted type adapted to run along the mine trackway and having kerf cutting mechanism adapted to operate while the apparatus is supported and guided by the mine trackway and means for propelling the apparatus by the drive 40 of the supporting wheels thereof, of supplemental propelling means for the apparatus operable simultaneously with the support wheel driving means comprising a haulage drum having end drum flanges and an intermediate flange 45 separating the drum winding surfaces, and a draft cable wound on one of said winding surfaces and having its free end wound upon the other winding surface of the drum whereby the cable may be wound in by said drum to effect 50 propulsion of the apparatus along the trackway in either direction without rewinding the cable on the drum.

10. The combination with a mining apparatus 55 of the wheel mounted type adapted to run along the mine trackway and having kerf cutting mechanism adapted to operate while the apparatus is supported and guided by the mine trackway, of propelling means for the apparatus comprising a haulage drum having end drum flanges and an intermediate flange separating the drum winding 60 surfaces, and a draft cable wound on one of said winding surfaces and having its free end wound in the reverse direction about the other winding surface of the drum whereby the cable 65 may be wound in by said drum to effect propulsion of the apparatus along the trackway in either direction without rewinding the cable on the drum.

11. The combination with a mining apparatus 70 of the wheel mounted type adapted to run along the mine trackway and having kerf cutting mechanism adapted to operate while the apparatus is supported and guided by the mine trackway, of propelling means for the apparatus comprising a haulage drum having an intermediate 75

flange separating the cable winding surfaces, a draft cable wound thereon, means for rotating said drum in either of opposite directions, and means whereby said cable may be wound in by said drum to effect propulsion of the apparatus along the trackway in either direction irrespective of the direction of rotation of the drum and without rewinding of the cable on said drum, the intermediate flange having an opening for passing the draft cable from one winding surface to the other.

12. The combination with a mining apparatus 80 of the wheel mounted type adapted to run along the mine trackway and having kerf cutting mechanism adapted to operate while the apparatus is supported and guided by the mine trackway, of propelling means for the apparatus comprising a haulage drum having end drum flanges and an intermediate flange separating the drum winding surfaces, and a draft cable wound on one of said winding surfaces and having its free end wound upon the other winding surface of the drum whereby the cable may be wound in by said drum to effect propulsion of the apparatus along the trackway in either direction without rewinding the cable on the drum, the intermediate flange having an opening for passing the draft cable from one winding surface to the other.

13. The combination with a mining apparatus 85 of the wheel mounted type adapted to run along the mine trackway and having kerf cutting mechanism adapted to operate while the apparatus is supported and guided by the mine trackway, of propelling means for the apparatus comprising a haulage drum having end drum flanges and an intermediate flange separating the drum winding surfaces, and a draft cable wound on one of said winding surfaces and having its free end wound upon the other winding surface of the drum whereby the cable may be wound in by said drum to effect propulsion of the apparatus along the trackway in either direction without rewinding the cable on the drum, the intermediate flange having an opening for passing the draft cable from one winding surface to the other.

14. The combination with a mining apparatus 90 of the wheel mounted type adapted to run along the mine trackway and having kerf cutting mechanism adapted to operate while the apparatus is supported and guided by the mine trackway, of propelling means for the apparatus comprising a haulage drum having end drum flanges and an intermediate flange separating the drum winding surfaces, and a draft cable wound on one of said winding surfaces and having its free end wound upon the other winding surface of the drum whereby the cable may be wound in by said drum to effect propulsion of the apparatus along the trackway in either direction without rewinding the cable on the drum, the intermediate flange having an opening for passing the draft cable from one winding surface to the other and the cable being wound upon one surface in one direction and on the other surface in the reverse direction.

15. The combination with a mining apparatus 95 of the wheel mounted type adapted to run along the mine trackway and having kerf cutting mechanism adapted to operate while the apparatus is supported and guided by the mine trackway, of propelling means for the apparatus comprising a haulage drum having coaxial winding surfaces, the drum having a flange arranged between said winding surfaces for separating said surfaces, said flange having an opening therein, and a draft cable wound on said drum surfaces and having an intermediate portion passing through said opening whereby the cable may be wound in by said drum to effect propulsion of the apparatus along the trackway in either direction and without rewinding the cable on the drum.

16. The combination with a mining apparatus 100 of the wheel mounted type adapted to run along the mine trackway and having kerf cutting mechanism adapted to operate while the apparatus is supported and guided by the mine trackway, of propelling means for the apparatus comprising a haulage drum having coaxial winding surfaces, the drum having a flange arranged between and separating said winding surfaces, said flange having a slot cut therethrough, and a draft cable wound on said drum surfaces and having an inter- 105

- mediate portion passing through said slot whereby the cable may be wound in by said drum to effect propulsion of the apparatus along the trackway in either direction and without rewinding the cable 5 on the drum.
16. The combination with a mining apparatus of the wheel mounted type adapted to run along the mine trackway and having kerf cutting mechanism adapted to operate while the apparatus is 10 supported and guided by the mine trackway, of propelling means for the apparatus comprising a haulage drum having coaxial winding surfaces, the drum having a flange arranged between said winding surfaces for separating said surfaces, said 15 flange having an opening therein, and a draft cable wound on said drum surfaces and having an intermediate portion passing through said opening, said cable being wound on one winding surface in one direction and on the other winding surface 20 in the reverse direction whereby the cable may be wound in by said drum to effect propulsion of the apparatus along the trackway in either direction and without rewinding the cable on the drum.
17. The combination with a mining apparatus of the wheel mounted type adapted to run along the mine trackway and having kerf cutting mechanism adapted to operate while the apparatus is supported and guided by the mine trackway, of 25 propelling means for the apparatus comprising a haulage drum having coaxial winding surfaces, the drum having a flange arranged between said winding surfaces for separating said surfaces, said flange having a slot cut therethrough, and a draft cable wound on said drum surfaces and having an intermediate portion passing through said slot, said cable being wound on one winding surface in one direction and on the other winding surface in the reverse direction whereby the cable may be wound in by said drum to effect propulsion of the apparatus along the trackway in either direction and without rewinding the cable on the drum.
18. The combination with a mining apparatus of the wheel mounted type adapted to run along the mine trackway and having kerf cutting mechanism adapted to operate while the apparatus is supported and guided by the mine trackway, of propelling means for the apparatus comprising a haulage drum, and a draft cable thereon having a single free end, said drum having means whereby a portion of said cable may be wound in one direction around said drum and another portion thereof in the reverse direction including an abutment on said drum around which an intermediate portion of said cable is adapted to pass whereby the 100 cable may be wound in by said drum to effect propulsion of the apparatus along the trackway in either direction and without rewinding of the cable on the drum.
